Patented Feb. 27, 1923.

1,447,096

This is a continuation of application filed April 1, 1920, Serial No. 391,008, and is entitled "Cleansing of Condensers and like Apparatus."

UNITED STATES PATENT OFFICE.

FRANCIS GRIMSHAW MARTIN, OF LIVERPOOL, ENGLAND.

CLEANSING OF CONDENSERS AND LIKE APPARATUS.

No Drawing.

Application filed December 15, 1920. Serial No. 431,008.

To all whom it may concern:

Be it known that I, FRANCIS GRIMSHAW MARTIN, a subject of the King of England, and residing at Liverpool, in the county of 5 Lancaster, England, have invented Improvements in and Connected with the Cleansing of Condensers and like Apparatus, of which the following is a specification.

This invention has reference to the cleaning of condensers and like apparatus connected with steam engines, and employed for condensing the steam discharged from them; and it has for its object to provide improvements whereby such cleaning is effected expeditiously, at a relatively small cost. In describing the mode of or means for cleaning condensers and like apparatus, it will be assumed that the condenser to be cleaned is one used for condensing the ex-

haust steam from marine engine of the usual type, and from the tubes of which matters with which the tubes are coated, viz, scale or like adhering matters, have to be removed.

In cleaning a condenser according to this 25 invention, a comparatively weak solution of nitric (or equivalent) acid is passed through the parts thereof for a suitable length of time, and after this has taken place, the acid solution is removed, and the apparatus is washed out with salt water, or fresh water.

The acid solution consists of a 4 per cent solution of nitric acid, or thereabouts; and this is circulated through the tubes and water boxes or chambers of the apparatus 35 until the adhering scale or matters are removed; and after the solution is removed water is passed through these parts, and all traces of the acid solution removed. By using acid of this strength the metal of 40 which the tubes are made is not detrimentally affected.

It is found by actual experiment that the above method and means effectively cleanses the interior of all parts of the apparatus, 45 viz, tubes and water boxes, in a comparatively short length of time, as when compared with the present mode of cleaning, which in many instances necessitates dismantling the apparatus and refixing, to ensure thorough cleansing of the tubes and other parts. Such a procedure takes days to accomplish whereas with the present invention, it is a matter of hours, such for instance as four hours, when the cleaning is

effected by the method and means set out above.

In carrying out the cleansing action, say in connection with a marine engine condenser, the main injection valve, and main discharge valve, are shut and the air escape 60 cocks on the top of the water boxes opened; and connection is made by piping to the top and bottom boxes or compartments of one water end of the condenser, and also to a pump provided for circulating the acid liquid. The liquid is held in a tank, say about a 20 gallon tank, and a connection made with the pump from same.

The proportion of acid used should not exceed 5 per cent by weight of the liquid, 70 and should be employed in the first instance to the strength of 4 per cent of the total amount of water used.

Before cleansing the condenser is to be thoroughly drained of sea-water before the 75 mixture of weak acid solution is pumped in and when the water boxes and tubes of the condenser are filled, which is ascertained by indications of the air escape cocks, the liquid is circulated through the condenser for about 80 one hour. Some of the liquid is then pumped overboard, and the condition of the tubes can be examined after removing a manhole door; and if the tubes are found to be sufficiently cleared the remainder of the mixture 85 is pumped overboard; but if scale is still found to be adhering to the tubes, a further supply of weak acid is pumped in, and the whole circulated again as before for another hour.

It is advisable, if practicable, to change the direction of the circulation each half hour.

On the completion of the cleansing or removal of scale and the condenser completely 95 pumped out, the condensing water circulating pump is set going at full speed, and left running for an hour on the condenser, to wash away any traces of acid remaining in the tubes and water boxes.

While the invention has been described as applied to the cleansing of condensers, it is also applicable to the cleaning of like apparatus, such as feed water heaters, evaporators, coolers, and the like, and particularly 105 those in which the tubes are made of metals of the kinds used in marine steam engine condensers.

What is claimed is:—

A method of cleansing condensers and the like apparatus, which consists in filling the same with a solution of nitric acid and water in which the proportion of acid to water does not exceed five per cent by weight, circulating the solution thru the apparatus by means of a pump until the scale or like incrustation has been sufficiently removed, emptying the apparatus of the acid solution and replacing same with water and finally

continuously circulating the water thru the apparatus by means of the pump until all trace of the acid has been removed.

In testimony whereof I have signed my name to this specification in the presence of two subscribing witnesses. 15

FRANCIS GRIMSHAW MARTIN.
